To all whom it may concern:

- Be it known that I, WILLIAM T. SMITH, a citizen of the United States, residing at Philadelphia, in the county of Philadelphia and 5 State of Pennsylvania, have invented and produced a new and original Design for a Woven Fabric, of which the following is a specification, reference being had to the accompanying drawing, forming a part thereof. 10 The leading features of my design are the representation of a peacock resting on a balustrade. On the right hand are buildings, cone-shaped and other trees, cone hills, and flowers at the base. On the left hand is a rep-

resentation of an ornamental vase and flowers. 15 At the lower left-hand corner is a floral representation. The whole is surrounded by an ornamental border and fringe.

Having as above fully described my invention, what I claim as new, and desire to secure by Letters Patent, is— 20
